INFANT GARMENT

Martha White Clark, Barrington, Ill.

Application March 7, 1932. Serial No. 597,225

2 Claims. (Cl. 2—111)

The invention relates to infant garments and more particularly to garments which are open only at the neck when in use, and which may be supplemented with other coverings when the weather is especially cold.

One of the objects of my invention is to provide a one piece garment for infants, the upper part of which fits snugly to the body of the infant so that it may turn over without disarranging the garment, while the lower part is in the shape of a bag to permit the infant to have freedom of use of its legs which at the same time cannot become uncovered. This will result in the child being warm at all times as the garment will not become disarranged but will allow full freedom of movement. In addition, the lower portion of the garment, while not hindering the infant from moving its legs, will prevent any supplementary covers which may be necessary from being disarranged or moved from their position.

While the upper part of the garment will fit snugly to a very small infant it will stretch so that it will fit the child when he becomes larger and will be able to be worn until the infant becomes a great deal older and larger.

Another object of my invention is to provide a garment with a long slit in the lower rear portion near one side through which the infant will be admitted and by means of which the child's lower undergarments may be changed when necessary without removing it from the garment, during which process the infant will remain warm as he will not be uncovered.

Another object of my invention is to provide a one-piece garment with sleeves and mittens thereon to keep the child's hands warm, and constructed in such a way that the child's arms and hands will stay in place in said sleeves and mittens although said members may be moved freely. This will insure that the infant's hands and arms will remain warm even if any outer covers become removed from these members.

Another object of my invention is to provide a one-piece garment with an opening at the top for the child's head which will be fashioned so as to fit snugly to the neck of the child, and be provided with a rolled collar so as to be certain to keep the infant's neck warm. In addition, the collar, being rolled, will not have to fit tightly to the infant's neck so that there is absolutely no danger of choking the infant. The infant will be able to have full freedom of movement of his head and neck without danger of these portions becoming cold and the collar will in no way interfere with, or disarrange a cap or bonnet which

may be necessary to cover his head, the lower edge of which cap or bonnet normally fitting intermediate the collar and the neck. And further, inasmuch as the garment is not attached to the head covering of the infant, all danger of choking which is caused by such attachment is eliminated without in any way permitting the infant's neck to become cold because of any open space between the garment and the head covering.

Moreover, as the garment and bonnet are not attached the movement of the infant's head will not be impeded thereby nor will there be any danger of the bonnet becoming disarranged which might occur because of such attachment, and thereby expose portions of the infant's head to the cold. It is also apparent that it will be very easy to carry the infant when in the garment and that he will remain warm while being carried.

The accompanying drawing discloses the preferred embodiment of my novel garment, but various changes and modifications may be made in such garment without departing from the spirit of my invention.

In the drawing:

Fig. 1 shows a front view of my garment showing how the same is worn by an infant; and

Fig. 2 is a rear view.

In a preferred embodiment as disclosed in the drawing, the reference character 1 represents the bag or lower portion of the garment which is knitted or formed with a closed bottom and sides. The sweater or upper part 2 of the body of the garment is knitted, as of knit and purl or ribbing stitch so as to fit snugly to a very small child but which will easily stretch or expand so as to fit a child as he grows older and larger. The sleeves 3 and the mittens 4 are both formed or knitted and connected at the wrists 5, the latter being constructed or formed as of knit and purl or ribbing stitch which fits snugly so as to keep the hands and arms in their proper places. The opening 6 at the front and top part of the garment permits insertion of the child's head therethrough and may be closed after the child is enclosed in the garment by ties, buttons, zippers, or the like 7.

The top portion of the garment is provided with a rolled collar 8. The rear portion of the bag or lower portion of the garment is formed with an opening or slit 9 spaced from the edge or side of the bag and adapted to be closed by ties, buttons, zippers or other means 10. By locating the opening 9 in this part of the garment, one is enabled to admit the child therein and to

change its lower undergarments very easily and quickly.

At the same time, because of its location, it will be practically impossible for him to put his foot through said opening 9 when he kicks his feet in the bag, especially when ties, buttons or the like are employed to close the opening. By the construction of the bag, the child may kick his legs about freely, while at the same time he is always completely covered. It will also make it exceedingly difficult for the child to disarrange or remove any supplementary covers which may be needed while he is sleeping. The garment is disclosed as made of relatively heavy material so that extra covers are not usually needed; but of course can be made of relatively light material for use indoors or in warm weather.

Having thus disclosed my invention, I claim:

1. An infant's garment of the character described comprising a close fitting body portion

provided with sleeves and having a neck opening, and a bag-like skirt portion closed at the front, back, sides and bottom and having its upper portion joined with said body portion, said skirt portion being wider at its lower end than at the part joined to said body portion, and provided with a longitudinal slit adjacent to one of the sides thereof.

2. An infant's garment of the character described comprising a body portion and a skirt portion constructed in one integral piece, said body portion being constructed and arranged to closely fit the body of the wearer and provided with sleeves and a neck portion, said skirt portion being closed at the front and back and on both sides and wider at its lower end than at its top, said skirt having a slit therein extending approximately from the waist line to the bottom and adjacent one side thereof.
